UNITED STATES PATENT OFFICE.

CLARENCE LESTER PITCHER, OF NEW YORK, N. Y.

ROLLING-PIN.

SPECIFICATION forming part of Letters Patent No. 643,780, dated February 20, 1900.

Application filed June 21, 1899. Serial No. 721,365. (No model.)

To all whom it may concern:

Be it known that I, CLARENCE LESTER PITCHER, a citizen of the United States, residing at New York, (Long Island City,) in the

5 county of Queens and State of New York, have invented certain new and useful Improvements in Rolling-Pins; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to rolling-pins; and its object is to provide means for reducing the friction incident to the use of a rolling-pin to the minimum.

The construction of the improvement will 20 be fully described hereinafter and its novel features defined in the appended claims.

In the accompanying drawings, which form a part of this specification, Figure 1 is a view in perspective of a rolling-pin embodying my 25 invention, and Fig. 2 is a longitudinal sectional view of the same.

The reference-numeral 1 designates a roller formed with a central bore 2, extending throughout the length of the roller, and with 30 circular end recesses 3, concentric with the bore. Within each of the end recesses 3 is secured a cup-bearing 4, having a cone-surface 5 and formed with central openings, through which extends a shaft 6. This shaft 35 projects beyond the ends of the roller 1 to support the handles of the device, and the ends of said shaft are reduced circumferentially and screw-threaded for the purpose hereinafter explained. The shaft 6 is also 40 screw-threaded at the points 7 for the attachment of bearing-cones 8, which latter have cone-surfaces coöoperating with the surfaces

5 to form a trackway for antifriction-balls 9. The bearing-cones 8 are formed with integral squared extensions 10, which facilitate their 45 adjustment.

11 and 12 designate the handles of the device comprising cylinders bored to fit the ends of the shaft and secured by caps 13, which are centrally bored and internally threaded 50 to engage the threaded ends of the shaft. The caps are held in place by screws 14, which pass through openings in the caps and into the ends of the handles.

It will be apparent from the drawings that 55 the roller 1 will freely revolve in use without revolving the handles, and, further, that the antifriction devices greatly reduce the labor of rolling dough.

I claim—

1. A rolling-pin comprising a roller formed with a central longitudinal bore, and end recesses concentric with said bore; antifriction-rollers supported within said recesses; a shaft 60 extending through the roller and projecting 65 from the ends thereof; and handles fixed to the ends of the shaft.

2. A rolling-pin comprising a roller formed with a central longitudinal bore, and end recesses concentric with said bore; cup-bearings secured within the recesses; a shaft 70 extending through the roller; bearing-cones on said shaft; antifriction - rollers supported within the recesses and between the cup-bearings and cones, handles on the ends of the 75 shaft; and caps for securing the handles to the shaft.

In testimony whereof I affix my signature in presence of two witnesses.

CLARENCE LESTER PITCHER.

Witnesses:

AARON JACOBS,
BENJ. W. PITCHER.
